UNITED STATES PATENT OFFICE.

LE ROY E. KNIGHT, OF BETHLEHEM, PENNSYLVANIA.

CURTAIN-POLE.

1,356,454.

Specification of Letters Patent. Patented Oct. 19, 1920.

Application filed September 13, 1919. Serial No. 323,488.

To all whom it may concern:

Be it known that I, LE ROY E. KNIGHT, a citizen of the United States of America, residing at Bethlehem, in the county of Northampton, and State of Pennsylvania, have invented new and useful Improvements in Curtain-Poles, of which the following is a specification.

This invention relates to curtain poles for the support of curtains or other draperies, and has for its object the provision of a curtain pole formed in longitudinally adjustable sections having engaged upon their outer ends block members adapted for engagement with the confronting faces of a door or window frame, the longitudinal relative movement of the sections permitting the pole to be extended and jammed within a door or window frame whereby the pole will be adequately supported merely by friction without the necessity for employing screws, nails, or other securing members, the block members having their faces covered with felt or other suitable material whereby to prevent injury to the finish of the wood-work.

An important object is the provision of a pole of this character which may be formed entirely of metal or of wood and metal, the adjustment in either case being the same and being effected by means of a screw having an operating head disposed for convenient engagement by an operator to effect proper adjustment.

Another object is the provision of a telescopically adjustable pole of this character in which the construction is such that the internal mechanism is at all times concealed regardless of the degree of extension of the pole so as to present always a neat appearance.

An additional object is the provision of a pole of this character which will be simple and inexpensive in manufacture, highly efficient in use, durable in service, and a general improvement in the art.

With the above and other objects and advantages in view, the invention consists in the details of construction to be herein-after more fully described and claimed, and illustrated in the accompanying drawings in which—

Figure 1 is a view of a door frame showing my pole in position therein and supporting drapery,

Fig. 2 is a longitudinal sectional view

through a pole construction in accordance with my invention and made entirely of metal,

Fig. 3 is a cross sectional view,

60

Fig. 4 is a side elevation showing my pole formed partly of wood and partly of metal,

Fig. 5 is a longitudinal sectional view, and

65

Fig. 6 is a cross sectional view.

Fig. 7 is an enlarged detail view of one end of the pole shown in Fig. 2, and

Fig. 8 is an enlarged detail view of one end of the pole shown in Fig. 5.

70

Referring more particularly to the drawings, the letter A designates a door frame, B designates my pole as a whole, and C designates drapery supported thereon.

In carrying out my invention I may form the pole entirely of metal, as in Fig. 2, or partly of metal and partly of wood, as shown in Fig. 4.

Referring especially to Fig. 2, it will be seen that my pole comprises sections 10 and 11 which are telescopically engaged. The section 10 has secured therein intermediate its ends a nut member 12 having a bore within which is engaged a threaded rod 13 extending longitudinally of the pole and carrying at the other end thereof a knurled or milled operating head 14. The rod 13 projects beyond the end of the section 11, as shown, and is engaged within a recess 15 formed in a block member 16 formed preferably of wood. This block member is inclosed within a metallic shell 17, and has a flat face covered with felt 18 adapted for engagement with one side of a door or window frame. At its outer end, the section 10 is engaged upon a reduced extension 19 formed upon a block 20 similar to the block 16. The head 14 is formed on opposite sides with grooved collars 14^a with which are engaged flanges 11^a and 17^a formed on the ends of the sections 10 and the shell 17, respectively.

In the use of this form of the device it will be seen that the pole is disposed within a door or window frame and the head 14 rotated to effect rotation of the rod 13. Rotary movement of the rod in the proper direction will cause relative longitudinal movement of the sections 10 and 11 which will result in longitudinal expansion of the pole to bring the flat felt covered faces of the blocks 16 and 20 into firm frictional en-

gagement with the door or window frame whereby to hold the pole securely in position. Owing to the engagement of the flanges within the grooved collar of the operating head, the rod will always be concealed and the pole will have a substantially smooth and neat appearance.

In Figs. 4, 5 and 6 I have shown the major portion of the pole 21 as formed of wood and this pole is provided in one end with a recess 22 within which is secured a nut member 23. One end of the pole 21 is received within a tubular extension 24 formed on a shell 25 surrounding a block 26 having a flat face covered with felt 27.

At its other end the pole 21 is slidably received within a tubular member 28. A rod 29 is disposed within this end of the pole and is threadedly engaged within the nut member 23 and this rod 29 carries an operating head 30. The end of the rod projects beyond the head 30 and is received within a socket 31 formed in a block 32 inclosed within a shell 32^a having a felt covered flat face 33, the construction of this block member being identically the same as that of the block member 16. The head 30 is provided on opposite sides with grooved collar 30^a within which are engaged flanges 28^a and 32^b formed respectively on the tubular member 28 and the shell 32^a.

In the use of this form of the device it will be seen that the operation is identically the same as in the previously described form, it being merely necessary to rotate the head 30 to effect longitudinal expansion of the pole. It will be noted that in this form the threaded rod will always be concealed.

From the foregoing description and a study of the drawings it will be apparent 40 that I have thus provided a very simple and inexpensive pole which is so formed that it may be expanded so that the end members carried thereby may be frictionally engaged within a door or window opening whereby 45 the pole will be adequately supported so as to sustain the weight of any draperies disposed thereon.

While I have shown and described the preferred embodiments of my invention, it 50 is of course to be understood that I reserve the right to make such changes in the form, construction, and arrangement of parts as will not depart from the spirit of the invention or the scope of the subjoined claim.

Having thus described my invention, I claim:—

A curtain pole comprising a pair of telescopically engaged sections, a jam engaging block member carried at the end of one section, the other section being provided at its end with an inturned annular flange, a nut member secured within said first named section, a threaded rod extending through both of said sections and engaging within 65 said nut, an operating head at the outer end of the second named section secured to said rod and having a collar engaged within said flange, said rod extending through said head, and a block member revolvably engaged upon the projecting end of the rod and having an inturned flange, said operating member having a second collar engaging within said second named flange.

In testimony whereof I affix my signature. 75
LE ROY E. KNIGHT.
